(57) **CLAIM**

The ornamental design for a “display screen or portion thereof with animated graphical user interface,” as shown and described.

DESCRIPTION

FIG. 1 is a front view of the first image of a display screen or portion thereof with animated graphical user interface; FIG. 2 is a front view of the second image thereof; FIG. 3 is a front detail view thereof, taken from FIG. 1 for clarity of illustration; and, FIG. 4 is a front detail view thereof, taken from FIG. 2 for clarity of illustration.

The dot-dashed broken lines show the display screen and form no part of the claimed design. The dot-dot-dashed broken lines define the boundary of the claimed design and form no part thereof. The remaining broken lines illustrate features of the graphical user interface and form no part of the claimed design.

The appearance of the image sequentially transitions between the images shown in FIGS. 1-2 and FIGS. 3-4.

The process or period in which an image transitions to another forms no part of the claimed design.
